Silk Spinning Mach.

Patented Jun. 29, 1833.

June 29. 1833 115.

7019 X Adams - 2 B 100 lbs

The following reference is in this Doctor's Patent and shall
be part of the same containing a description in the words
of the said Adam Davis himself of his improvement
in the machine for spinning silk.

To all to whom these presents shall come. We the undersigned
of Adam Davis,
Inhabitants in the County of Plymouth and State of Mass-
achusetts have invented a new and useful improvement
in the art of spinning silk and the following is a full
and exact description and exp. of the construction and op-
eration of the said machine as invented or improved
by me. Figure 1 represents the top of the machine. Figure
2. the side, and Figure 3 the front. A a trough about 31
inches long, 16 inches wide and four inches deep filled
with boiling water into which the cocoons are put after being
prepared for spinning. B. a common stone furnace filled
with coals to keep the water hot. C. is a slippery board
about 24 inches wide and 24 feet long passing through
a hatch in the bar D. on the sides of which are placed
cabled wires through which the fibers are collected and
carried through the leading wires E. E. to both ends
back from thence over the top roller F. and then between
the rollers through the cabled wires. The fibers are to the
spools G. G. which are similar to those common in cotton
mills whose spindles are turned by the wheels i.e. with
horses from thence to the drum H. which has a large
wheel on one end of its axle connected by brass or leather
to the large wheel which may be turned by hand, or if require-
d to do more easily the number of spindles may be
increased and horses, steam or water power applied. This
method of spinning silk is first of all applicable for
the purpose of making for silk the various kinds of
clothing and household articles, & may be used for

They have received upon a sufficient quantity, and placing them on the pins $\{$, from which the threads of two or more are carried through the leading wires $\{$, and connect the wire b , and from thence over the upper roller and under the base b , around the wire b , $\{$ fig 3. thence back over the upper and between the rollers same as before to the fiber c , the middle and tail of which are turned by a band around the flange of the frame D , a band or belt passing over the top roller and round the small wheel C , binds down the roller so as to draw the silk gradually forwards from the cocoon and spools through the wires to the fibers and also produces the vibrating motion of the slide b , by raising and lowering the slide to receive the thread equally, according to the cleat for particular dimensions. That I claim as my invention, was put in operation previous to the twenty-seventh of 2° Month Oct. 1833 and relates to arranging the collecting and leading wires nearly in a range so as to draw the thread even and not break the fibers as they would by circular turns and collecting fibers enough from the cocoon at once to make a thread of any size that may be wanted, and drawing them ^{evenly} round the upper to make it pass through the rollers even to the spools and spinning it immediately wet in its natural gum in the best manner, into a finished thread. Also that of having a band or belt to pass over the top roller round the small wheel and draw the two fold purpose of binding down the top roller so as to draw the thread and carry the wheel producing the vibrating motion for the spools, whether the method of doubling the ~~one~~ thread for drawing silk, by drawing the single thread separate around the wires till they come together to make them double ones and then passing over the top roller round a hook under the top bar, then drawing the ~~one~~ thread

wishes to make it draw even before it is twisted, when
drawing the fibers from the cocoons by a steady, uniform
breaking the fibers less than by pulling in the common way,
without less from splitting in tangling, much finer, smoother,
stronger (and more even than any other method) and with
great dispatch. The other parts of the machine having been
in use before I only claim their application.
